(57) **CLAIM**

The ornamental design for a holster, as shown and described.

DESCRIPTION

FIG. 1 is a front top perspective view of a first embodiment of a design for a holster;

FIG. 2 is a front view of the first embodiment of the design for the holster;

FIG. 3 is a rear view of the first embodiment of the design for the holster;

FIG. 4 is a right side view of the first embodiment of the design for the holster;

FIG. 5 is a left side view of the first embodiment of the design for the holster;

FIG. 6 is a top view of the first embodiment of the design for the holster;

FIG. 7 is a bottom view of the first embodiment of the design for the holster;

FIG. 8 is a front top perspective view of a second embodiment of the design for the holster;

FIG. 9 is a front view of the second embodiment of the design for the holster;

FIG. 10 is a rear view of the second embodiment of the design for the holster;

FIG. 11 is a right side view of the second embodiment of the design for the holster;

FIG. 12 is a left side view of the second embodiment of the design for the holster;

FIG. 13 is a top view of the second embodiment of the design for the holster; and,

FIG. 14 is a bottom view of the second embodiment of the design for the holster.

The features shown in broken lines depict environmental structure only and form no part of the claimed design.

1 Claim, 14 Drawing Sheets
